(57) **CLAIM**

The ornamental design for a wire rack, as shown and described.

DESCRIPTION

FIG. 1 is a perspective top view showing our new design for a wire rack.

FIG. 2 is a perspective top view of an alternative configuration of the wire rack of the present invention.

FIG. 3 is a top view of the wire rack shown in FIG. 1.

FIG. 4 is a perspective front view of the wire rack shown in FIG. 1.

FIG. 5 is a right side view of the wire rack shown in FIG. 1, the left side view being the mirror image thereof.

FIG. 6 is a back view of the wire rack shown in FIG. 1.

FIG. 7 is a bottom view of the wire rack shown in FIG. 1.

FIG. 8 is a top view of the configuration of the wire rack shown in FIG. 2.

FIG. 9 is a perspective front view of the configuration of the wire rack shown in FIG. 2.

FIG. 10 is a right side view of the wire rack shown in FIG. 2, the left side view being the mirror image thereof.

FIG. 11 is a back view of the wire rack shown in FIG. 2.

FIG. 12 is a bottom view of the wire rack shown in FIG. 2.

FIG. 13 is a bottom right perspective view of the wire rack shown in FIG. 1; and,

FIG. 14 is a bottom right perspective view of the wire rack shown in FIG. 2.
